JOSHUA HARRISON, OF BROOKLYN, AND GEORGE W. HARRIS, OF NEW YORK, ASSIGNORS
TO THEMSELVES AND CHARLES H. HUDSON, OF NEW YORK, N. Y.

Letters Patent No. 66,835, dated July 16, 1867.

IMPROVED CLOTHES-WRINGER.

The Schedule referred to in these Letters Patent and making part of the same.

TO ALL WHOM IT MAY CONCERN:

Be it known that we, JOSHUA HARRISON, of Brooklyn, in the county of Kings, and State of New York, and GEORGE W. HARRIS, of the city, county, and State of New York, have invented certain new and useful Improvements in Clothes-Wringers; and we do hereby declare that the following is a full, clear, and exact description thereof, reference being had to the accompanying drawings, and to the letters of reference marked thereon.

The object of our invention is to produce or furnish a clothes-wringer which shall at the same time be cheaper, more durable, and easier in its operation than other first-class machines now in use; in which the passage between the rolls of an article of more than usual thickness, requiring more than the usual amount of power to be applied to turn the rolls, will cause the fastenings which secure the machine to the tub to hold more firmly, and in which the rolls fall apart when the machine is removed from the tub, thereby preventing injury to the rolls by their being left screwed tightly together after having been heated by use.

The devices and combinations of parts by which these results are secured, and which constitute our invention, are—

First, the combination in a clothes-wringer of one cork and one rubber roll, by which the machine is rendered cheaper and more durable than similar machines with two rubber rolls, and as durable and much easier in its operation than a machine in which two cork rolls are employed.

Second, the combination with the rubber roll and cork roll of a long, curved, or elliptic spring, and a bar across the top of the machine, against which the middle of said spring rests, by which the upper roll is pressed down against the clothes operated upon, and which yields to allow a thick article to pass between the rolls.

Third, the combination with the rubber roll, cork roll, spring, and bar, of bent levers hung at one end to the frame of the machine, and bearing against the tub at the other end; the lower roll being hung at the angle in such a manner that any downward pressure on the lower roll will cause the lower end of said bent lever to bear more firmly against the tub; and so that when the machine is removed from the tub, the said lower roll may drop down sufficiently to remove it from contact with the upper roll. For this purpose the slots in the frame in which the journal-boxes which support the rolls play are so arranged that when both rolls are at their lowest point, as they are when the machine is not in use, there shall be a slight interval or opening between the faces of the rolls. By this construction the fastenings which secure the wringer to the tub hold more securely by aid of the bent levers when it becomes necessary to apply extra power to drive the rolls; and when the machine is removed from the tub the rolls fall apart, and there is no danger of one of them becoming flattened by being screwed tightly against the other, as frequently happens with machines heretofore used. By means of the fastenings shown, the wringer may be secured to a round or square tub with equal security and facility, thus increasing the range of usefulness of each machine without adding to its cost. In the accompanying drawings—

Figure 1 is a side elevation of my improved wringer.

Figure 2 is an end elevation of the same.

Figure 3 is a vertical cross-section through the centre.

A and B are the end pieces of the frame; C is a rubber roll, and D a cork roll; E is the top bar of the frame, against which the spring F, the ends of which bear on the journal-boxes *aa* of the roller C, and press it down, reacts. G is another rod or bar which connects the end pieces A and B at or near their centres, and completes the frame. The end pieces A and B have each two slots in their upper ends, the upper slots being for the journal-boxes *aa* to work in, and the lower ones for the journal-boxes *bb* to work in. The lower ends of these slots are just far enough apart so that when the journal-boxes *aa* and *bb* rest in the lower ends of their respective slots the surfaces of the rolls are just removed from contact with each other. The lower ends of the end pieces A and B are forked so as to enable them to grasp the tub or other article for containing the clothes; and one of the forks of each end piece is supplied with a set-screw, L, by which the wringer is screwed to the tub. H and I are the bent levers hung to the rod G at their upper ends, and bearing against the tub at or near their lower ends. At the elbow or angle of these bent levers, seats or bearings *b* are provided for the shaft K to work in. These seats or bearings *b*, when the machine is not in use, rest in the bottom of the lower

slots in the end pieces A and B of the frame. When the machine is placed on the tub and the screws L tightened, the lower ends of the bent levers H and I are thrown out, thus raising the roll D, which in turn presses up the roll C, the spring F yielding sufficiently for that purpose.

The machine being now ready for use, the articles to be wrung are successively introduced in the usual manner between the rolls, and the lower roll turned by a suitable crank on the shaft K, which forces or draws the clothes through the machine and expresses the water. When the thicker portions of the articles pass between the rolls, the roll C is pushed upward, the spring F yielding for that purpose, and the pressure of the spring F downward upon the roll C is transmitted through the clothes and roller D to the bent levers H and I, causing their lower ends to press more firmly against the tub. On removing the machine from the tub, the pressure on the lower ends of the bent levers H and I is removed, and the lower roll is then free to drop down and free itself from contact with the upper roll, whereby any danger of the rubber roll becoming permanently flattened by continued pressure after being heated by use is avoided. By the use of the cork roll as the driving-roll there is no longer any necessity nor advantage in the use of cog or toothed wheels to connect the rolls, as the cork roll is sufficiently strong and durable to sustain the strain to which it is subjected, and the lower roll is the one which usually gives way or becomes injured where two rubber rolls without toothed gearing are employed.

We claim as our invention—

1. The combination in a clothes-wringer of a cork roll and a rubber roll, substantially as and for the purpose set forth.
2. The combination, with the cork roll D, and rubber roll C, in a clothes-wringer, of the spring F and bar E, substantially as set forth.
3. The combination, with the end pieces A and B forked at their lower ends, the rolls C and D, and the spring F, of the bent levers H and I, the said bent levers being so constructed and arranged as to accomplish the results set forth, substantially as hereinabove specified.

JOSHUA HARRISON,
GEO. W. HARRIS.
